UNITED STATES PATENT OFFICE

2,410,617

HAIR CURLER

Sebastian Wirsing and Rosa Wirsing, Long Island
City, N. Y.

Application February 13, 1945, Serial No. 577,618

3 Claims. (Cl. 132—33)

1

This invention relates to hair curlers and has for its object to provide means for curling a strand of hair and placing a pair of "bobby" pins or the like thereon.

Another object of the invention is to provide a member upon which a strand of hair may be curled, having means for retaining the end of the hair to be formed into the curl, said means being adapted to being withdrawn after the curl has been formed and during the withdrawal thereof attach a pair of clips to the curl to hold the same secured.

Another object of the invention is to provide a U-shaped member having means for holding and applying to a curl of hair a pair of clips.

Other features and advantages will become more readily apparent from the following description and the accompanying illustrative drawing in which:

Figure 1 is an elevational view of my device,

Figure 2 is another elevational view thereof,

Figure 3 is an enlarged end view of Figure 1, and

Figure 4 is an elevational view showing a curl secured by a pair of clips.

In the accompanying drawing as above enumerated and in the following specification, like characters of reference indicate like parts throughout and in which 10, indicates my invention which comprises a U-shaped member 11, having arms 12 and 13, to the lower ends of which are secured clips 14 and 15, the arms 16 and 17 of which are inserted through passages 18 and 19, formed in the terminals 20 and 21, of said arms 12 and 13. To the lower end of the arm 12, is fixed a spring clip 22, adapted to cross the space 23, between the arms 12 and 13, and the end 24, of which bears against the inner surface of the arm 13. The elongated outer arms 25 and 26, of the clips 27 and 28, the arms 16 and 17, of which are frictionally held in said passages 18 and 19, are turned out as at 29 and 30, but engage the arms 12 and 13, frictionally at the bends 31 and 32, of said terminals 29 and 30.

In use a suitable strand of hair for forming a curl is pushed in between the terminals 20 and 21, of the said member 11, and up towards its head portion 33, which strand will be engaged and held by the spring end 24, whereupon the

2

user wraps the strand around the member 11, until a curl is formed of suitable diameter, then the said head 33, is held between the fingers of the user and gradually pulled from the curl which action will cause the upturned ends 29 and 30 to pass over the outer surfaces of the curl 34, and the inner arms 16 and 17, of the clips 27 and 28, will be drawn within the curl and against the inner surfaces thereof, whereby the curl will be securely held by the said clips or "bobby" pins 27 and 28. After the curl has been held a sufficient time to form the curl, the said clips are removed.

It is thought that persons skilled in the art to which the invention relates will be able to obtain a clear understanding of the invention after considering the description in connection with the drawing. Therefore, a more lengthy description is regarded as unnecessary.

Minor changes in shape, size and rearrangement of details and parts such as come within the purview of the invention claimed may be resorted to, in actual practice, if desired.

Having now described our invention that which we claim as new and desire to procure by Letters

25 Patent is:

1. A hair curler comprising a U-shaped member and a spring fixed to one arm thereof and detachably engaging its other arm, the terminal of said arms being apertured and a pair of clips each having a straight arm for seating in one of the apertures and a curved arm bearing against the U-member arm to which it is attached.
2. A curler having arms with tubular ends, a spring clip having a straight arm projecting into one of the tubes and having an arm outwardly of the tubular end and bearing there-against at one point, a spring intermediate the curler arms and fixed to one thereof and bearing movably against the other, and a similar arranged clip carried by the other curler arm.
3. A curler having arms with tubular ends, a spring clip having a straight arm projecting into one of the tubes and having an arm outwardly of the tubular end and bearing there-against at one point, and a spring intermediate the curler arms and fixed to one thereof and bearing movably against the other.
